UNITED STATES PATENT OFFICE.

THOMAS F. MURPHY, OF UTICA, NEW YORK.

SAFETY-CATCH FOR JEWELRY.

1,300,856.

Specification of Letters Patent. Patented Apr. 15, 1919.

Application filed February 28, 1917. Serial No. 151,576.

To all whom it may concern:

Be it known that I, THOMAS F. MURPHY, of Utica, in the county of Oneida and State of New York, have invented certain new and useful Improvements in Safety-Catches for Jewelry; and I do hereby declare that the following is a full, clear, and exact description thereof, which will enable others skilled in the art to which it appertains to make and use the same, reference being had to the accompanying drawings, and to the reference numerals marked thereon, which form part of this specification.

My present invention relates to safety catches for pin tongs of jewelry.

The purpose of my invention is to provide a novel and improved form of safety catch for the pin tongs of jewelry and the like.

20 In the making of jewelry such as pins, class pins, brooches and the like where a pin tong is hinged at one end to the pin and its free end or point is detachably secured to a keeper, it has been a serious 25 problem to provide an efficient safety catch which would prevent the accidental disengagement of the pin from the keeper. The small size of the safety catch has been one 30 obstacle in providing a practical and reliable catch. Inasmuch as many of the class pins to which the safety catch is to be applied are less than half an inch in diameter, it will be seen that the safety catch must be very small and often is required to be 35 less than a sixteenth and even less than a thirty-second of an inch in width. On account of this extremely small size of the device many forms of mechanism which would be practical on a larger article are 40 not practical and not reliable for the purpose in hand.

Another serious obstacle in providing a safety catch is the fact that these catches in practice have to be made separately from 45 the pin or other article of jewelry by the manufacturer and are afterward affixed to the separate pins by the retail or repair jeweler. The usual and proper way to fasten the safety catch to the body of the pin 50 is by the hard soldering process. During such process of hard soldering the adjacent part of the body of the pin and the safety catch have to be brought to a very high temperature. This high temperature operates to take the temper out of all parts 55 of the catch thus preventing the use of any

forms of mechanism that require the metal to be tempered. Furthermore this high temperature operates to distort, warp and otherwise change the shape and fit of parts 60 so that where any mechanism requiring one part to fit closely or coöperate closely with another part is used such adjustment is lost during the soldering process, resulting in the device being entirely spoiled or requiring 65 so much hand-work and adjustment to be expended upon the article as to render the device expensive and unreliable. The heat of the soldering process is especially disastrous where a pivoted member is a 70 part of the catch as usually the pivoted part has become solid and has to be loosened and re-adjusted by hand.

It is one main purpose of my invention to provide a safety catch which will obviate 75 the disadvantages above named and at the same time provide an economical and thoroughly practical and efficient safety catch and one which may be readily affixed to the pin or other article of jewelry without any of the disadvantages above named.

A further purpose of my invention is to provide a safety catch wherein the keeper and the movable part are of such form and coöperate in such manner that the movable 85 part may be readily attached to the keeper after the keeper has been affixed to the body of the pin and so that the said movable part may be attached to the keeper by a very simple operation which may be properly 90 done by even an inexperienced operator rapidly and without the use of special tools. In other words, the movable part is an open-ended loop of such construction that it is attached to the keeper by the simple act of 95 temporarily expanding the loop which may even be done by forcing it down on the keeper and allowing the inturned pintle points of the loop to spring into place in the keeper. It follows from what has been 100 said that it is a further purpose of my invention to provide a device wherein the keeper may be readily affixed to the body of the pin and then the movable part attached thereto or detached therefrom without 105 impairing the efficiency of either part or the coöperation of said parts.

Another object of my invention is to provide a safety catch of such form that it may be applied to a considerable variety of 110 forms of keepers with equal efficiency and particularly to provide a form of safety

catch that is adapted to be used with either a receiver having its pin tong receiving recess in its top or a keeper having its receiving recess in its side.

5 Further purposes and advantages of my invention will appear from the specification and drawings herein.

Figure 1 is a side elevation on an enlarged scale of a clasp pin embodying my invention 10 with the pin tong partly open.

Fig. 2 is a similar side view but with the pin tong in closed position but with the safety catch still in open position.

Fig. 3 is a similar view showing the pin 15 tong and safety catch both closed.

Figs. 4, 5 and 6 are back views of said pin with its parts in the position shown respectively in Figs. 1, 2 and 3.

Figs. 7, 8, 9 and 10 are respectively side, 20 exterior face, interior face and top views on a still further enlarged scale of the keeper.

Fig. 11 is a side view on a similar scale of the movable part or spring loop.

25 Fig. 12 is a similar view of another form of the spring loop.

Fig. 13 is a back view of a pin having a hook-shaped keeper embodying my invention.

30 Fig. 14 is a side view on an enlarged scale of the keeper shown in Fig. 13.

Fig. 15 is a perspective view of the keeper and loop of the form of my invention shown in Figs. 13 and 14.

35 Referring to the drawings in a more particular description, it will be seen that I have shown my safety catch applied to the back or rear surface of the body 20 of a pin or other form of jewelry having the usual pair of upwardly extending ears 21 between 40 which one end of the pin tong 22 is fastened by the usual pivot 23 leaving the point end 24 of the pin tong free to be inserted through the clothing in the usual way and 45 then fastened to the keeper.

Referring now to the form of my invention shown in Figs. 1 to 11 inclusive, it will be seen that the safety catch of my invention comprises a keeper 25 and a spring loop 26. The keeper 25 has its bottom surface secured in any desired way, but usually by a hard soldering process to the back surface of the pin 20. The top of the keeper has a recess 27 therein of such size and so located as to be adapted to receive thereinto the point end 24 of the pin tong 22. On the opposite sides of the keeper 25 and close to the bottom of the keeper are provided inwardly-extending recesses 28 adapted to receive the inturned pintles 29 of the spring loop 26. Preferably the opposite sides of the keeper will be provided with grooves 30 extending from the pintle recesses 28 to the top of the keeper. Preferably also the 65 top of the keeper will have a transversely-

extending groove 31 connecting the grooves 30 on the opposite sides of the keeper and extending across the top of the keeper except that it is of course interrupted where the deeper recess 27 cuts across the top of the keeper in the opposite direction.

The spring loop 26 is formed of any suitable material that will be somewhat springy or resilient and which will retain such resiliency and be strong and durable for the 75 work in hand as well preferably also as being similar in appearance to the other metal of the piece of jewelry so as not to detract from the appearance of the article. The spring loop 26 is formed as plainly indicated in the drawings to be generally U-shaped in form with the bow portion 32 and opposite sides or leg portions 33 at the ends of which are formed inturned and oppositely disposed pintles 29. The said loop 80 is attached to the keeper by temporarily springing the sides of the loop apart until the pintle points are opposite the pintle recesses 28 when the spring loop is allowed to again contract or spring back into normal 85 shape. The spring loop 26 and keeper 25 are so shaped in proportion to each other that the loop 26 with its pintles 29 in the keeper recesses 28 is pivotally mounted upon the keeper and may be moved from the 90 open position shown in Figs. 1 and 4 to the closed position shown in Figs. 3 and 6.

The safety catch is of such proportion and so located upon the pin 20 that when the loop 26 is moved from open to closed 100 position it will swing past the point 24 of the pin tong 22 in the keeper 25 and come to position with the bow 32 of the loop above or over the pin tong 22 a little back from the point 24 of the pin tong as plainly indicated in Figs. 3 and 6. It will be obvious that with the loop 26 in such closed position the pin tong cannot be moved away from the keeper 25 until the safety catch loop 26 is swung back from closed or lock- 110 ing position.

Suitable means are provided whereby the spring loop 26 strongly tends to remain in closed or locked position. One of the means I prefer to use for this purpose are the 115 grooves 30 on opposite sides of the keeper in line with the closed position of the loop so that when the loop has come to closed position it will contract sufficiently to have its sides 33 fit into said grooves 30 with a decided locking action so that no ordinary handling of the pin or accidental moving of the pin will move the spring loop out from its closed position. The groove 31 on the top of the keeper also assists in the same 125 way in retaining the loop in closed position. Of course the half or part of the receiver from the groove 30 toward its outer face is wider and also preferably higher than the part of the keeper inclosed within the loop 130

when the loop is in locking position and so operates to positively prevent the spring loop from freely swinging back to open position. The wide parts of this half of the keeper are indicated by the numerals 34 which are really shoulders past which the spring loop can be swung by sufficient power being applied to the spring loop to spring its sides 33 slightly apart. The shoulders 35 at the top of this half of the keeper are preferably of such height as to retard the bow of the loop as it passes over said shoulders thus aiding to keep the loop in closed position. It will be obvious that the holding of the loop in locked position and against its moving to opened position may be effected by having high spots or projections at any suitable place corresponding with either the shoulders 34 or 35 without having said high spots extend all the way around the top and sides of the loop as shown and without having the decided grooves 30 and 31 in the sides and top of the keeper as shown.

While it is obvious that the spring loop might be allowed to pass entirely over the keeper and so extend toward the ears 21, such construction is inconvenient in that it would require the user to see that the spring loop was first turned outward to the position shown in Fig. 1 before attempting to lock the pin. I prefer, therefore, to positively prevent the spring loop from being moved farther inward than closed position. This is accomplished by high or wide spots such as shoulders 36 on the top of the keeper or shoulders 37 on the side of the keeper or preferably as shown by having both sets of shoulders. With the safety catch so constructed the spring loop will have to be moved to open position in order to remove the pin from the clothing and then the slight spring tension of the loop against the keeper will ordinarily hold the loop in open or unlocked position ready for the next locking operation.

For greater convenience in operation the loop 26 may be provided with an outwardly projecting thumb or finger clip 38 as shown in Fig. 11 or such finger clip may be formed by having a decided kink 39 formed in the loop at that point as shown in Fig. 12.

Referring now to the modification of my invention as shown in Figs. 13 to 15 inclusive, it will be seen that this retains the spring loop and its spring function as herein shown but that the keeper 40 is of the common hook-keeper formation having an opening 41 at one side with a pin-receiving recess 42 in which the pin tong rests while it is held from being accidentally moved therefrom by reason of the spring loop 26 now closing the opening 41. The spring loop 26 is of the same construction as already described and is pivoted to the keeper 40 as already described with reference to the keeper 25 and

held in the side grooves 30 and top groove 31 by reason of side shoulders 34^a and a top shoulder 35^a and held from passing beyond closed position by shoulders 36^a and 37^a similar to shoulders 34, 35, 36 and 37 already described.

It will now be obvious that the safety catch I have shown permits of the keeper 25 or 40 being securely fastened by even a hard-soldering process to the body 20 of a pin without injuring any moving or sliding part for the reason that the loop 25 is not at that time in place upon the keeper and the heat or other steps necessary to fasten the keeper to the pin do not affect the shape, holes, recesses 80 or shoulders of the keeper. After the keeper is thus fastened upon the pin the pin may be subjected to any further process of manufacture such as that of enameling without injuriously affecting the keeper. After the pin 85 is otherwise entirely completed the spring loop 26 is attached to the keeper in an obvious manner by simply springing the sides of the spring loop apart which generally will be done by forcing them gently down in the 90 grooves 30 until the pintles 29 spring into the pintle recesses 28. It will be obvious that this may be done by unskilled operators such as boys or girls. It will further be seen that these spring loops may be readily detached from the keeper if the loop needs replacement or if the rest of the pin needs any repairing work done thereupon which will involve the use of high temperature.

It will be seen that in the form of my invention as shown in Figs. 13 to 15 the keeper 40 bears the pull or strain of holding the pin tong to the pin and the spring loop 26 simply prevents the lateral displacement of the pin tong from the keeper. This form of my invention is particularly useful when the pin is of such value as to make it inadvisable to rely entirely upon the spring loop for the main function of holding the pin tong upon the pin.

What I claim as new and desire to secure by Letters Patent is:

1. A safety catch for pin tongs of articles of jewelry comprising a keeper having oppositely disposed pintle recesses and guiding 115 grooves leading to said recesses, combined with a locking spring loop having inturned ends forming pintles adapted to enter said recesses, said loop being thus adapted to be manually applied to said keeper and being 120 pivotally mounted so that it may be turned to hold or release the pin tong.

2. A safety catch for pin tongs of articles of jewelry comprising a keeper having a main recess to receive a pin tong, and having pintle 125 recesses near the base of its sides, combined with a U-shaped spring loop having its ends inturned to form oppositely disposed pintles fitting said pintle recesses of the keeper and adapted to retain the pin tong in the said 130

main recess and to be turned back to uncover the said main recess to allow the pin tong to be removed therefrom, said loop being adapted to be affixed to the keeper by temporarily 5 springing the loop apart and entering the pintles into the said pintle recesses of the keeper.

3. A safety catch for pin tongs of articles of jewelry comprising a keeper having a 10 main recess to receive a pin tong, and having pintle recesses near the base of its sides, combined with a U-shaped spring loop having its ends inturned to form oppositely disposed pintles fitting said pintle recesses of the 15 keeper and adapted to retain the pin tong in the said main recess and to be turned back to uncover the said main recess to allow the pin tong to be removed therefrom, said keeper having guiding grooves extending to said 20 said pintle recesses to direct said pintles into said recesses, said keeper being provided with means for retaining said spring loop in closed position, and said loop being adapted to be affixed to the keeper by temporarily

springing the loop apart and entering the 25 pintles into the said pintle recesses of the keeper.

4. A safety catch for pin tongs of articles of jewelry comprising a keeper having a main recess to receive a pin tong and having 30 pintle recesses near the base of its sides, combined with a U-shaped spring loop having its ends inturned to form oppositely disposed pintles fitting said pintle recesses of the keeper and adapted to retain the pin tong in 35 the said main recess and to be turned back to uncover the said main recess to allow the pin tong to be removed therefrom, said keeper having guiding grooves extending to said 40 pintle recesses to direct said pintles into said recesses, said keeper being provided with means for retaining said spring loop in closed position, and said keeper also having stop means for preventing said loop from swinging past its proper closed position. 45

In witness whereof I have affixed my signature, this 27th day of February, 1917.

THOMAS F. MURPHY.
